CLAIM

The ornamental design for an incontinence pad, as
shown and described.

DESCRIPTION

FIG. 1 is a plan view of an incontinence pad, showing
our new design;

FIG. 2 is a plan view thereof, opposite that shown in
FIG. 1;

FIG. 3 is a side perspective view thereof; and

FIG. 4 is a side elevational view thereof.

FIG.1

FIG.2

FIG.3

FIG.4
